UNITED STATES PATENT OFFICE.

WILLIAM LADUE POST, OF COLD SPRING, NEW YORK.

BRAKE-SHOE.

1,139,798.

Specification of Letters Patent. Patented May 18, 1915.

Application filed July 25, 1914. Serial No. 853,041.

To all whom it may concern:

Be it known that I, WILLIAM LADUE Post, a citizen of the United States, and resident of Cold Spring, in the county of Putnam and State of New York, have invented a certain new and useful Brake-Shoe, of which the following is a specification.

This invention relates to brakes for wheeled vehicles, and its object is to provide a brake that is marked by simplicity while retaining the highest efficiency.

The objects are attained by the means set forth in this specification and the accompanying drawings.

Reference being made to the drawings, Figure 1 is a front elevation of the brake shoe, with the rubbing shoe omitted. Fig. 2 is a reverse view of the shoe as shown in Fig. 1. Fig. 3 is a longitudinal section of the brake shoe. Fig. 4 is a longitudinal section of the brake shoe in its normal position. Fig. 5 is a perspective view of the adjusting collar.

This brake shoe comprises only five parts, exclusive of the shaft: a casing *a*, collar *b* that holds the casing in place on the shaft, a spiral spring *d* which retains the shoe in a normal position and admits of the shoe adapting itself to the face of a wheel, a rubbing shoe *u* held between the flanges of the casing, and a set-screw in the collar. The brake shoe is carried upon the shaft *s* which may form a part of any suitable braking mechanism.

The casing *a* is a single casting, or it may be stamped or forged into shape. It comprises a curved back with flanges *r*, the outer edges of the flanges having overhanging flanges *t*, Figs. 1 and 4, the opposite flanges forming a dove-tail between them, for holding the rubbing shoe *u* shown in Fig. 3. To provide bearing surfaces adequate for long service shoulders *l* are provided inside the casing around the shaft.

A collar *b* shown in perspective in Fig. 5, is adjustable on the shaft *s*. The collar has a segmental projection *m* on its periphery, and a slot *o* in the back of the casing, Figs. 1, 2, 3, 4 receives the collar projection, as most clearly shown in Figs. 3, 4. A spiral spring *d* is placed within the casing on the shaft beside the collar. A set-screw *c* in the collar serves to secure the collar in position on the shaft. A lug *i* is provided at one end of the casing to which the long end *d¹* of the spring is hooked, as at *e*, Figs. 1,

2, and 3. The other end *d²* of the spring engages over one shoulder of the collar projection *m* as in the first four figures.

In assembling this brake shoe the collar and spring are held in place within the casing the projection on the collar within the slot in the back of the casing, and the shaft is passed through the three parts. One end of the spiral spring is engaged with a shoulder of the collar projection, and the long end of the spring is hooked over the lug at the end of the casing. In Fig. 4 the long end of the spring is shown to be engaged with a hole in the casing, as at *e¹*. The point at which the end *d¹* of the spring is secured is really immaterial so long as the tension of the spring upon the casing is properly obtained. This fact is illustrated by the different positions in which the spring end *d¹* is shown in the drawings, and they are so shown in order to emphasize this point. The action of the spring is to turn the casing on the shaft and normally to keep the shoulder *n* in the slot *o* against the shoulder *v* of the projection *m*, as in Figs. 1, 2 and 4.

No special preparation of a shaft is required, other than to have a sufficient length of it to fit the bores of the collar and the casing for lateral adjustment of the brake shoe. Adjustments of the brake shoe are made entirely with the collar, and the collar is secured by the set-screw. The normal position of the brake shoe in relation to a wheel will be as shown in Fig. 4, the line *w* representing the wheel. When the brake shoe is thrust against the wheel the lower end of the shoe first touches the wheel and is pressed backward, which moves the top of the shoe forward. The position of the shoe against the wheel will be as in Fig. 3, the line *w* representing the wheel. It will be seen that the collar projection *m* will then be midway of the slot *o*, allowing the shoe self adjustment against the wheel, the spring making it a firm adjustment.

Having described my invention, what I claim and desire to secure by Letters Patent, is—

1. The combination in a brake shoe of a casing, means in the casing for holding a rubbing shoe, shaft bearings in the casing to receive a shaft, a shaft through the casing, a collar on the shaft within the casing and a segmental projection on the collar, a slot in the back of the casing to admit the

extension on the collar, a spiral spring on the shaft acting between the collar and the casing, and a set-screw in the collar.

2. The combination comprising the automatic adjusting parts of a brake shoe, of a shaft, a casing on the shaft, a collar on the shaft within the casing, a projection on the collar, a slot in the casing to admit the collar projection, a set-screw in the collar, and 10 a spring on the shaft within the casing to act between the collar and the casing.

3. The combination in a brake shoe of a shaft, a casing movable on the shaft, a rubbing shoe attached to the casing, a collar 15 on the shaft within the casing, an extension

on the collar and a set-screw in the collar, a slot in the back of the casing to receive the projection on the collar, a spiral spring on the shaft within the casing, a lug on the end of the casing, one end of the spring engaged 20 with the collar projection the other end of the spring attached to the lug on the end of the casing.

Signed at Cold Spring in the county of Putnam and State of New York this 14 day 25 of July A. D. 1914.

WILLIAM LADUE POST.
